UNITED STATES PATENT OFFICE.

GERALD DOD, OF SOUTHPORT, ENGLAND.

STEAM EJECTOR OR EXHAUSTING APPARATUS.

1,181,067.

Specification of Letters Patent.

Patented Apr. 25, 1916.

Application filed November 30, 1915. Serial No. 64,373.

To all whom it may concern:

Be it known that I, GERALD DOD, a subject of the King of England, and resident of Southport, in the county of Lancaster, England, have invented new and useful Improvements Connected with Steam Ejectors or Exhausting Apparatus, of which the following is a specification.

This invention has reference to the removal of, and dealing with dust or dirt, or granular matter, from flues of steam generator and other furnaces, and from other analogous chambers; and more particularly to that system wherein the dust and dirt or like matters, are moved by a vacuum created within a vessel by a steam ejector, and the matters so collected are subsequently discharged from the vessel or container in which they have been collected; and this invention has primarily for its object, to provide means or modes of operation herein-after described, by which the action of the apparatus is rendered more efficient and silent, and the construction of the apparatus or modes of operating are generally simplified and improved.

According to this invention, a receiver or vessel or vessels is or are provided in the dust or dirt removing apparatus—in addition to the main dust depositing vessel—into which the steam jet exhausting apparatus discharges; and back pressure in this receiver or vessel into which the steam, air, and some dust or dirt are discharged and expanded, is avoided by condensing the steam entering the receiver or vessel with the air, by introducing a stream or jets of water into the receiver or vessel at or near the point of delivery of the air and steam into it, into contact with or through which water, the air and steam mixed with it pass; and in coming in contact with the water, the steam is condensed, the result of which is that back pressure, which would otherwise exist in the receiver or vessel, is obviated, and therefore the efficiency of the ejector or ejectors is maintained at a high degree. Also, on the outlet pipe or branch in the vessel into which the exhaustors discharge, there is provided a silencing device consisting of a perforated pipe or "rose", by which the creation of the noise by the exhaust is obviated. The dust which passes through the ejectors with the steam and air forms only a small portion of the total dust moved; the bulk being

collected and deposited in the main receiver or vessel.

The above improvements will be further described in connection with the accompanying drawings which illustrate them.

In these drawings Figure 1 is an elevation of the complete plant for the removal of and dealing with dust, or dirt, or granulated matter of the kind herein referred to; and Fig. 2 is a side elevation; Fig. 3 shows a modification, and Fig. 4 is a section showing in detail the means employed for obviating the noise created by the steam exhausters, and preventing or obviating back pressure in the vessels or chambers into which the steam and air are discharged.

Referring to the drawings, 1 represents generally the vessel into which the dust or dirt or matter carried by the air is introduced, and wherein it separates out from the air; 2 is the conduit through which the air and dust or dirt is conveyed from the place of deposit of the dust, say for example a furnace flue, to the vessel 1; 3 are the steam jet ejectors—of which there are two—connected with the upper part of the vessel 1 for creating vacuum within the vessel; 4 is the pipe for supplying the ejectors with steam; 5 is the steam supply regulating valve, which may be assumed to be operated by a device within the vessel 1 which is actuated by the presence of dust in the vessel 1 upon its being deposited therein, such device being connected with the valve 5 by the rod 6 in the known way.

7 are vessels into which the discharge of air, steam, and a small quantity of dust delivered from the steam jet exhaustors takes place; and 8 is the final air discharge pipe.

9 is the dust discharge door in the vessel 1; 9^x is its operating rod; and 10 a weighted lever, fulcrumed at 11, connected with the rod 9^x which opens the door when released.

12 is a vessel surrounding the discharge door 9, and discharge mouth of the vessel 1, into which the contents of the vessel 1 are discharged. The vessel 12 has a conical and diminishing discharge or lower part 13; and it is provided with an aperture 14, which is normally closed by a cover opposite the door 9, so as to obtain access to it if required. The vessel 12 keeps the dust or dirt from coming into contact with air in discharging from the discharging door 9, and from flying about, and acts as a gen-

eral quieting chamber to the discharging dust.

With regard to the means for obviating the noise created by the steam ejection, this comprises an expanding cone device 16 surrounding the discharge nozzle of the ejector 3, as hereinafter described with reference to Fig. 4, and depending down into the vessel 7 as shown, the lower part of the device being cylindrical; and a perforated pipe or rose 17, also depending a short distance down into the vessel 7, and on the upper part of same. This perforated rose or pipe 17 forms the lower end of the air discharge pipe 8.

The bottom of each vessel 7 is coned at 18, so as to carry off the liquid which is discharged into the cone 16, as hereinafter described, and the dust caught by it; and this liquid is carried by the pipe 19 from the condensing and silencing vessels 7 into the tank 20 having a valve 21 on it, which is controlled as hereinafter described for the purpose specified.

Referring now more particularly to Fig. 4, this figure shows the mode of introducing the water to the ejector apparatus, and the discharge cone devices 16, for condensing the ejector steam, and preventing back pressure. The water for condensing the steam is introduced by way of an annular port 22, in and extending around the outer casing 23 of the discharge cone 24 of the ejector, through which the steam, and dust carried by it, are delivered into the device 16; and from this port 22 the water passes by a plurality of holes 25 into an annular space 26 surrounding the cone 24, at the bottom of which is a loose plate 27, with gaps or holes in it, or having an annular space between it and the cone 24, of regulated area, for controlling the quantity of water. By this arrangement, from the lip of the discharge ejector cone 24 there flows a ring spray or stream of water; and the steam issuing into the space within this ring of water comes into contact with it and condenses, and so prevents the existence of material back pressure, in the vessel 7, which would if it existed interfere with the free discharge of the air from the ejectors, and in consequence their efficiency and their creating powers.

When dust or like removing apparatus of the kind referred to is arranged to discharge into a cart, truck, or the like, which is to convey it away, the condensing water, and the water of condensation, are adapted automatically to deposit any fine dust which may arise from the bulk discharging from the vessel 12, or it might be by the door 9, if no vessel as 12 were used. This water, as stated, in the case shown, is collected in the tank 20, and is conducted by the pipe 32 to the rose or other sprayer 33 in, around, or adjacent to the discharge end or mouth

of the vessel 12, and so arranged that the downward spray falls on any rising dust from the body of dust being discharged, and so moistens it and settles it. This spraying is arranged and adapted to take place when the door 9 is opened; and the opening of this door is controlled or effected by a piston in the cylinder 30, one end of which is connected by a pipe 31 with the steam pipe 4, so that when steam is supplied to this pipe 4 by the opening of the valve 5, and so to the ejectors 3, it is also supplied to the top of the cylinder 30, and presses the piston of it down; and the piston being connected to the door operating weighted lever 10, by the double links 34, it moves it against this lever, about the fulcrum 11, and so keeps it closed; and while so closed, the valve 21, which is on the pipe 22*, and which is also connected with the links 34, is also closed, being pressed down on to its seat. On the other hand, when the steam is cut off from the ejector exhausters 3, and the pressure in the cylinder 30 is relieved, the weight of the lever 10 will simultaneously open the discharge door 9, and the water valve 21, and allow the water from the tank 20, to flow to the spraying rose 33.

In some cases, the discharge door 9 of the vessel 1 is automatically operated or controlled by the water from the condensing or silencing vessel or chamber 7—or by water otherwise supplied; and one mode of accomplishing this is illustrated in Fig. 3. Namely, in this case, within the tank 20, to which the water is supplied, there is employed a floater device 35, say a cup floater, connected to the lever 36, which operates the steam supply to the exhauste ejectors; and when the water rises in the tank 20, the floater 35 also rises lifting the lever 36 about its fulcrum 36*. This continues until the valve comes on to its seat and closes, and when closed the vacuum is destroyed. When the vacuum is on the dust discharge door of the main vessel—spindle 9* of which is seen in Fig. 2—will be held up to its seat by the external pressure of the atmosphere; but when off, the discharge door opens by its own weight, or is assisted by a weight. Should, however, the door stick when the pressure is removed, the float 35 will continue to rise until a pin 38 in the double links 34—through the space between which the door lever 10 passes—acts on this lever, and so forces the door open; whereupon the lever 10, being free to rise at this end, does so, and the door falls; at the same time the lever 10 and links 10* open the valve 21 and allow the water from the tank 20 to pass to the spraying rose 33. When the door is open, the lever 10 comes on to another pin 39 extending through links 34. The level of the water in the tank 20 then drops, and the float 35 falls with it, slowly, so bringing

down the lever 36, which is arranged to open the valve and admit steam to the ejectors 3. In the falling of the lever 36, the pin 39 being in contact with the upper edge 5 of the lever 10 causes the door end of the lever 10 to rise slowly, and so slowly closes the door; while at the same time, at the end of the stroke, the valve 21 is again closed; and the water again passes into the tank 20, 10 and again rises in it, and the operation described is repeated.

Instead of the float device, in an open tank, being used, as described, a tipping basin, or other similar hydraulic actuating 15 device, into which the liquid falls from the vessel 7, or other timed or measured source of supply, may be employed.

When the operation of this dust collecting and discharging apparatus is operated 20 or controlled by the mode described with reference to Fig. 3, the use of a device within the dust vessel which, through the presence of the dust therein, causes the actuation of the ejector steam supply control 25 valve, is rendered unnecessary, the apparatus itself being worked by the liquid supplied to the hydraulic appliance, which upon a given quantity being supplied, over a given period, cuts off the steam supply to the ejector, and so causes the door to open; so that the dust or dirt or the like collects over a given period of time, and then discharges 30 automatically.

What is claimed is:—

35 1. Apparatus for removing dust, dirt and granular matter from flues of steam generators, furnaces and other chambers, comprising a collecting vessel; a steam ejector for creating a vacuum within the collecting vessel; water supply means for condensing the steam discharged from the ejector; and means for subsequently applying and using the condensing water for preventing the rising of dust from the volume or body there- 40 of when being discharged from the apparatus; substantially as described.

2. In an apparatus of the class described, the combination of main and auxiliary vessels, a door at the discharge end of the main 50 vessel, means for supplying water to the auxiliary vessel, a tank receiving the water discharged from the auxiliary vessel, a discharge pipe leading from the tank to the main vessel, a valve in the discharge pipe, 55 a weighted lever connected to the door, a connection between the weighted lever and the valve, whereby the latter and the door are simultaneously operated, and means for controlling the valve and the door.

60 3. In an apparatus of the class described, the combination with a main collecting vessel, a door at the discharge end of the main collecting vessel, an auxiliary collecting vessel, a pipe between the main and auxiliary vessels, an ejector in the pipe, means in-

cluding a valve for supplying the ejector with steam, means for supplying the exit of the pipe in the auxiliary vessel with water, a tank for receiving the water discharged from the auxiliary vessel, a discharge lead- 70 ing from the tank to spray the dirt discharged from the main receiving vessel, a valve in the discharge pipe, means between the door and the valve in the discharge pipe for simultaneously operating same, and 75 a connection from the last mentioned means to the steam valve for operating the latter to stop the ejector when the door is opened.

4. In an apparatus of the class described, the combination of a main receiving vessel, 80 a door at the discharge end thereof, an auxiliary vessel, an ejector between the main and auxiliary vessels for forming a vacuum in the main receiving vessel and injecting steam in the auxiliary vessel, means for sup- 85 plying water to condense the steam and settle the dust in the auxiliary chamber, a tank into which the water from the auxiliary chamber discharges, a pipe leading from the tank and discharging the water 90 to the path of the dirt discharged from the main receiving chamber, and automatic means controlled by the water in the tank for controlling the ejector, the door, and the valve. 95

5. Apparatus for removing dust, dirt and granular matter from the flues of steam generators, furnaces and other chambers; comprising in combination a collecting chamber, a steam ejector; a vessel into which 100 the ejector discharges; a water jet steam condensing means in the said vessel; a water tank adapted to receive the water from the vessel; a discharge door to the collecting chamber; and a water regulating valve connected with the discharge door and operating in connection with it. 105

6. Apparatus for moving dust, dirt or granular material from flues of steam generators, furnaces and other chambers, comprising a main vessel having a discharging part, a door therefor, an auxiliary vessel connected with the main vessel, means for creating a partial vacuum in the main vessel and discharging into the auxiliary vessel, 115 means for supplying water to the auxiliary vessel, a secondary vessel into and through which the dust or dirt from the main vessel is discharged, and means actuated by the water from the auxiliary vessel for operating the door and simultaneously supplying water to the discharge end of the secondary receiving vessel to prevent the rising of dust from the body of dust being discharged. 120

7. Apparatus for moving dust, dirt or 125 granular matter from flues of steam generators, furnaces, and other chambers, comprising a dust and dirt collecting vessel having a discharging door or device; a vessel enclosing the said discharging door or device 130

adapted to receive the dust and dirt when discharged; a steam ejector; water supply means for condensing the steam of the steam ejector; means for collecting the water after the condensing action; and means for subsequently applying such water to the settling of the dust, dirt or granular matter discharged from the collecting vessel.

8. An apparatus for removing flue dust and the like including a main receiving vessel, a steam ejector having its vacuum end connected thereto, a secondary receiving vessel, a valve for controlling the supply of steam to the ejector, a water spray located at the discharge end of the ejector, said spray discharging into the secondary receiving vessel, a discharge door at the lower end of the main receiving vessel, an auxiliary vessel located at the lower end of the main vessel and into which the door is designed to open, a tank for receiving accumulated water from the secondary receiving vessel, a discharge pipe leading from said tank and into the auxiliary vessel, a valve in the discharge pipe, said valve being

adapted to be controlled by the door operating means.

9. In an apparatus of the class described, the combination of a main receiving vessel, a steam ejector having its vacuum end connected thereto, an auxiliary receiving vessel, a water spray located at the discharge end of the ejector, said spray discharging into the auxiliary receiving vessel, a discharge door at the lower end of the main receiving vessel, a tank for receiving accumulated water from the auxiliary receiving vessel, a discharge pipe provided with a valve leading from said tank to deliver a spray to the dirt discharged when the door is opened, and means for simultaneously opening and closing the door and valve.

In testimony whereof I have signed my name to this specification in the presence of two subscribing witnesses.

GERALD DOD.
